(57) **CLAIM**

The ornamental design for a bottle, as shown and described.

DESCRIPTION

FIG. 1 is a front, top perspective view of a bottle showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is rear, bottom perspective view thereof;

FIG. 9 is a front, top perspective view thereof in a used state; and,

FIG. 10 is a rear, bottom perspective view thereof in a used state.

The broken lines in FIGS. 9 and 10 are for the purpose of illustrating the environmental structure and form no part of the claimed design.
